UNITED STATES PATENT OFFICE

2,467,007

VIBRATING AND MASSAGING APPARATUS

Frederick Boyd, Montgomery, Ala.

Application July 12, 1946, Serial No. 683,206

5 Claims. (Cl. 128—52)

1

The present invention relates to new and useful improvements in vibrating and massaging apparatus, and more particularly to devices of this character for applying heat to and for vibrating and massaging the scalp or head.

An object of the invention is to provide a device of the above character which may be placed directly on the head and which may be heated and vibrated electrically.

Another object of the invention is to provide an improved head and scalp vibrator which shall contain an adjustable heating element particularly for use after oil shampoos.

A still further object of the invention is to provide a device of the above character which shall comprise alternative massaging elements for use in operation upon heads of various sizes.

A still further object is to provide a rigid hood for the head having a sectional massaging element positioned therein and forming a liner for the hood, the sections of the liner being positioned over the top and at either side of the head, and arranged for alternate massaging movement.

An additional object is to provide a device of this character of simple and practical construction, which is efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming a part hereof, wherein like numerals refer to like parts throughout, and in which:

Figure 1 is a side elevational view with parts broken away and shown in section.

Figure 2 is a front elevational view also with parts broken away and shown in section.

Figure 3 is an enlarged fragmentary sectional view taken on a line 3—3 of Figure 1.

Figure 4 is an elevational view of the device illustrating its appearance as a complete commercial product.

Referring now to the drawings in detail, wherein for the purpose of illustration I have disclosed a preferred embodiment of the invention, the numeral 1 represents a standard, supported in a base 2 and having secured thereto by means of a thumb nut 3 a curvaceous arm 4 from which is dependent the heating, massaging and vibrating unit shown generally at 5, and which represents the novel portion of the device. Secured directly to the arm 4 is a housing 6 for containing a small electric variable speed drive

2

motor 7 and a suitable 4-to-1 reduction gear train 8, the details of which are not deemed to be inventive, and which are consequently not described in detail.

The housing 6 is secured on top of a rigid hood 9 adapted to be placed over the head of a person, the hood having a pair of laterally extending shafts 10 journaled thereon and extending toward each side of the hood, the inner ends of the shafts being provided with bevel gears 11 operatively engaging the last gear 12 of the gear train 8.

To the outer end of each of the shafts 10 is secured a bevel gear 13 driving a similar gear 14 connected eccentrically to a disc 15 by means of a shaft 16, which is journaled in an opening 17 of the hood 9 at one side of the latter.

The eccentric disc 15 is positioned to travel in an oval-shaped race or track 18 from the opposite sides of which a pair of slides 19 project, the slides being mounted for reciprocating movement in arcuate slots 20 formed in the hood 9.

A sectional massaging element is designated generally at 21, and is constructed of rubber or similar material reinforced with wire mesh 22, the massaging element embodying a right and a left section, 23 and 24, respectively, forming a two-part liner covering substantially the entire inner surface of the hood and connected to the respective slides 19 by snap fasteners or the like 25.

The meeting edges of the sections 23 and 24 of the massaging element extend from front to rear of the hood, and are provided with opposed tracks 26 of channel-shaped construction for riding against the opposite sides of rollers 27 journaled at the under side of the hood, whereby the sections of the massaging element may travel forwardly and backwardly under the hood and against the scalp of a person upon a reciprocating motion of the slides 19.

Secured to the hood 9 is an electric switch 28 and a rheostat 29 controlled by means of a knob 30, all electrically connected in series with a heating coil 31 positioned between the hood and the massaging element 21. The switch 28 serves to connect the motor 7 to a source of current (not shown) and also connects the heating coils 31 to the same source of current. The rheostat 29 serves to control the amount of heat generated in the heating coils 31 by controlling the current flowing therein and may be suitably calibrated in terms of temperature, if desired. The heating coils 31 must, of course, be thoroughly in-

sulated from the hood 9, and this may be accomplished preferably with an asbestos lining 32.

In the operation of the device it will be apparent that the shafts 10 at the opposite sides of the hood are oppositely rotated, whereby to move the massaging elements 23 and 24 oppositely over the scalp of a person through the eccentric 15 and slides 19.

It is believed that the details of construction, manner of use and advantages of the device will be readily understood from the foregoing without further detailed explanation.

It is to be understood, however, that even though I have herein shown and described a preferred embodiment of my invention, the same is susceptible of certain changes fully comprehended by the spirit of the invention as herein described, and the scope of the appended claims.

Having thus described the invention, what I claim is:

1. A scalp-massaging device comprising a rigid hood shaped to receive the top and back portions of a head, a sectional scalp-massaging lining in said hood conforming to the internal configuration of the latter, a pair of slides mounted for reciprocation one at each side of said hood and each connected to a respective lining section for movement of the latter within said hood, respective drive means for said slides journaled in said hood, an electric motor mounted on said hood, and means operatively connecting said motor with said drive means including a bevel gear journaled on said hood, a bevel gear on each drive means, respective shafts, each having a bevel gear on each end thereof, connecting said drive means bevel gears with said first-mentioned bevel gear, and a speed-reducing gear train between said motor and said first-mentioned bevel gear.

2. A scalp-massaging device comprising a rigid hood shaped to receive the top and back portions of a head, a sectional scalp-massaging lining in said hood conforming to the internal configuration of the latter, a pair of slides mounted for reciprocation one at each side of said hood and each connected to a respective lining section for moving of the latter within said hood, respective drive means for said slides journaled in said hood, an electric motor mounted on said hood, means operatively connecting said motor with said drive means including a bevel gear journaled on said hood, a bevel gear on each drive means, respective shafts, each having a bevel gear on each end thereof, connecting said drive means bevel gears with said first-mentioned bevel gear, and a speed-reducing gear train between said motor and said first-mentioned bevel gear, and a hollow housing on said hood inclosing said

motor and said means connecting said motor with said slide drive means.

3. A scalp-massaging device comprising a rigid hood shaped to receive the upper and back portions of a head, means for supporting said hood, a two-part, scalp-massaging lining of resilient material in said hood covering substantially the entire inner surface of the latter, a pair of slides mounted in said hood, one in each side thereof, for reciprocation in a forward and backward direction and respectively connected to the lining parts, respective drive means for said slides journaled in said hood, an electric motor mounted on said hood, and speed-reducing gear means operatively connecting said motor with said slide drive means.

4. A scalp-massaging device comprising a rigid hood shaped to receive the upper and back portions of a head, means for supporting said hood, a two-part, scalp-massaging lining of resilient material in said hood covering substantially the entire inner surface of the latter, a pair of slides mounted in said hood, one in each side thereof, for reciprocation in a forward and backward direction and respectively connected to the lining parts, respective drive means for said slides journaled in said hood, an electric motor mounted on said hood, speed-reducing gear means operatively connecting said motor with said slide drive means, and an inner lining of heat-insulating material fixed in said hood.

5. A scalp-massaging device comprising a rigid hood shaped to receive the upper and back portions of a head, means supporting said hood, a two-part, scalp-massaging lining of resilient material in said hood covering substantially the entire inner surface of the latter, a pair of slides mounted in said hood, one in each side thereof, for reciprocation in a forward and backward direction and respectively connected to the lining parts, respective drive means for said slides journaled in said hood, an electric motor mounted on said hood, speed-reducing gear means operatively connecting said motor with said slide drive means, a respective track on the inner edge of each lining part, and anti-friction means carried by said lining between said lining parts and engaged by said tracks.

FREDERICK BOYD.
